UNITED STATES PATENT OFFICE.

HENRY LAURENCE, OF CHICAGO, ILLINOIS.

DENTAL DRILL-TOOL HOLDER.

SPECIFICATION forming part of Letters Patent No. 249,844, dated November 22, 1881.

Application filed June 29, 1880. (Model.)

To all whom it may concern:

Be it known that I, HENRY LAURENCE, of the city of Chicago, in the State of Illinois, have made certain new and useful improvements in the means and method of holding and detaching drill and other tool points from the brace or other holding device for holding them, of which the following is a specification.

Figure 1 shows the form of the drill or any tool-point used. Fig. 2 is a sectional view, showing the construction of the socket, with the spring for holding drill-point in position. Fig. 3 is a sectional view of holding device, showing a different view from that shown in Fig. 2. Fig. 4 shows the drill in position, ready for use.

I will describe only such parts of the mechanism as are necessary to show my improvement.

The drill point or tool P is made in the form shown in Fig. 1. About one-half of the drill-point is cut away at the head, and about one-half of the remainder is cut away, leaving a shoulder at S, Fig. 1. The socket or hollow shaft wherein the drill is inserted is made to conform to the cut-away part of the drill-point. A slight portion of this filled space of the hollow shaft is cut away, as at t, Fig. 3, which leaves a circular space, less one-quarter of the drill P, (shown at S,) for the admission of this shoulder S. On the half-filled space in the

hollow shaft q is attached a spring, O, Figs. 2 and 3. The drill P is inserted in the hollow shaft q, and the halved end passes over the half-filled space in said hollow shaft, and in so doing the spring O is compressed, and when pushed in sufficiently far the drill is turned by the pressure of the spring one quarter around, thus throwing the shoulder S, Fig. 1, into the recess t, Fig. 3, which securely locks the drill in place while in use. In removing the drill it is turned backward, thus compressing the spring, and unlocks the engaging-shoulders.

It will be observed that the fastening device is confined to the hollow of the shaft, requiring no external appliances. It will be understood that it is not designed to work the drill in that direction which will cause the power of the drill to work against the spring O, this serving only to hold the drill in position.

I claim as follows:

The hollow shaft q, having the rear end of the tube partially filled, and with the recess t and spring O, all arranged for the purpose of securing the drill P and holding it in position, substantially as shown and described.

HENRY LAURENCE.
